UNITED STATES PATENT OFFICE.

HENRY A. STONE, OF SCOTCH PLAINS, NEW JERSEY.

SPUTUM-CUP HOLDER.

1,294,563.

Specification of Letters Patent. Patented Feb. 18, 1919.

Application filed July 31, 1918. Serial No. 247,626.

To all whom it may concern:

Be it known that I, HENRY A. STONE, a citizen of the United States, residing at Scotch Plains, in the county of Union and 5 State of New Jersey, have invented certain new and useful Improvements in Sputum-Cup Holders; of which the following is a specification.

This invention relates to sputum-cup holders and the object of the invention is to produce a simple, inexpensive and efficient device by which the cups will be supported against collapse and may be very easily removed when filled. A further object of the 15 invention is to provide a device which may be applied to any of the sputum cups now on the market and which will support the cup when in use so that contact with the contents of the cup will be avoided.

20 The invention is illustrated in the accompanying drawings and will be hereinafter fully described, the novel features being subsequently particularly pointed out in the claims.

25 In the drawings—

Figure 1 is a perspective view of a sputum cup supported within my improved holder;

Fig. 2 is a longitudinal section through the cup and the holder supporting the same;

30 Fig. 3 is a detail perspective view of the holder and the cover mounted thereon.

In carrying out my invention, I employ a single strand or length of stout wire and, midway the ends thereof, bend the said 35 strand or length of wire into a rectangular loop 1, the end portions of the wire being brought together at one side of the loop and then bent downwardly, as shown at 2, a clip or sleeve 3 being passed around said down-

40 turned portions so as to hold them together. Below the said clip 3, the branches of the wire are doubled on themselves to form the eyes or handle member 4 projecting rearwardly from the down-turned portion 2 and

45 from the said eyes or handle member the branches of the wire are carried downwardly in spaced relation, as indicated at 5. The spaced portions 5, together with the down-turned portion 2, will constitute a support

50 or brace for the back wall of the cup 6 and should, therefore, be of such length as may be necessary to accommodate a cup of standard height. From the lower ends of the spaced portions 5, the branches of the wire

55 are carried forwardly in divergent paths to form the base members 7 upon which the

cup rests, and the front ends of these base portions 7 are turned upwardly to provide the front arms 8 which extend up to the loop 1 and have their extremities formed into 60 eyes 9 which encircle the front portion or side of the loop 1. The cup 6 is of any desired construction and is generally a stout impervious paper receptacle of rectangular form having its upper edges folded over 65 into the interior of the cup, as shown at 10. The cup is inserted downwardly through the loop 1 and rests upon the base members 7 so that the sides of the cup will be supported by the top loop 1 and thereby maintained in 70 proper shape.

A cover 11, preferably of sheet metal, is provided to extend over the top of the cup and prevent the escape of infectious matter and germs therefrom, the said cup being 75 provided with a handle 12 at its rear edge and also provided with a down-turned flange 13 at said edge which is constructed with a central notch 14 to accommodate the upper sides of the eyes or handle 4 and also 80 to permit a spring 15 to be coiled around the rear side of the loop 1 and have its ends engaged respectively over the rear edge of the cover and the down-turned portion of the holder. The edge of the flange 13 85 is rolled upon itself to provide a sleeve or hinge member 16 which fits around the side of the loop 1 so as to permit the cover to turn pivotally upon the loop, the spring 15 holding the cover normally over and upon 90 the top of the cup and the handle member 12 permitting the cup to be raised against the tension of the spring as will be readily understood upon reference to Figs. 1 and 3.

95 It will be readily understood that this improved holder is formed of a single length of wire and may be, therefore, very cheaply and easily manufactured. When in use it will firmly support the cup so that it will not collapse and may be repeatedly used until filled and when filled may be easily removed from the holder to be destroyed in accordance with the usual practice. A new cup may, of course, be very readily inserted into the holder and a single holder, therefore, used indefinitely. The holder is light 100 and so that it may be handled by a weak invalid and it will not occupy so much room that its use will be prohibited.

Having thus described the invention, what 110 is claimed as new is:

1. A device for the purpose set forth com-

- prising a single strand of wire formed midway its ends into an upper receptacle-engaging loop, the end portions of the strand meeting at one side of the loop and then extending downwardly therefrom and then doubled on themselves to form eyes adjacent the down-turned portions and extending downwardly from said eyes at the sides of the first mentioned down-turned portions,
- 5 then extending forwardly in diverging paths in a plane approximately parallel with the receptacle-engaging loop and terminating in up-turned members having their ends connected to the front side of the receptacle-
- 10 engaging loop, and means for holding the first mentioned down-turned portions together.
2. A device for the purpose set forth comprising a single strand of wire formed midway its ends into an upper receptacle
- 15 engaging loop, the end portions of the strand

meeting at one side of the loop and then extending downwardly therefrom and then doubled on themselves to form eyes adjacent the down-turned portions and extending 25 downwardly from said eyes at the sides of the first mentioned down-turned portions, then extending forwardly in diverging paths in a plane approximately parallel with the receptacle-engaging loop and terminating in 30 up-turned members having their ends connected to the front side of the receptacle engaging loop, means for holding the first mentioned down-turned portions together, and a spring-controlled cover provided at 35 one edge with spaced hinge sleeves engaging around the side of the receptacle-engaging loop at opposite sides of the down-turned portions of the same.

In testimony whereof I affix my signature. 40

HENRY A. STONE. [L.S.]
